UNITED STATES PATENT OFFICE.

HERMANN DEPPERMAN, OF NOWAWES, NEAR POTSDAM, GERMANY.

SUPPORT AND BRAKE FOR BOBBINS OF SPINNING MACHINES.

Application filed September 22, 1925, Serial No. 57,819, and in Germany September 27, 1924.

This invention relates to spinning machines of the type wherein rotatable flyers are operative to spin the fibre into yarn and said flyers arranged in relation to the spools 5 to lay the yarn thereon as it is spun and the bobbins adapted to be rotated through the pull thereon by the yarn to compensate for the difference in the rate at which the yarn is spun and the rotation of the flyer about 10 the bobbin, means being provided to yieldingly retard the rotation of the bobbin by the pull of the yarn, and it is the object of the present invention to provide an improved construction and arrangement of 15 bobbin support and mounting therefor and to drag or brake mechanism to yieldingly retard the movement of the bobbin support and whereby to maintain a dragging or retarding effect upon the bobbin of a constant 20 predetermined force proportional with the tensile strength of the yarn.

In carrying out the invention the spindle upon which the bobbin is engaged is mounted to have free and easy rotation in a lifter 25 and flyer frame, preferably in a ball bearing, with the spindle extending from one side of said frame for engagement of the bobbin thereon and being provided with means to co-operate with the bobbin to positively couple the bobbin to the spindle to rotate therewith. The lifter frame is in the 30 form of a box and the spindle is arranged so that an end portion thereof extends beyond its bearing into the frame and has a friction wheel or disk fixed thereto, said disk being in the nature of a brake drum for the 35 frictional engagement of means arranged within the frame to retard and exert a dragging or retarding force thereon and thereby 40 on the spindle, said means being adjustable from the exterior of the frame to vary said dragging force, and the drag or brake mechanism being enclosed in the frame thereby preventing the accumulation of foreign substances 45 thereon, such as lint thrown off from the fibre being spun, and interfering with the proper functioning of said mechanism.

In known constructions of spinning machines arranged with active flyers having downwardly extending arms and with dead spindles, the bobbins are usually loosely placed upon the spindles, whether the lifter frame is of the rotatably supported or linearly displaced form. The spindles are fixed 50 upon the frame or are rotatably mounted thereon, and the bobbins are rotatable on

the spindles at a constantly varying and uncontrollable speed, with the result that in either case a sudden and jerky frictional resistance is produced and a sudden slack and kink in the spun yarn produced. To overcome this disadvantage rotatable metal tubes are secured to the bobbins and located between the latter and the spindle. However, by this arrangement a tensile strain must 60 be exerted upon the yarn in the course of spinning to move the bobbin and the tube to overcome the frictional resistance between the stationary supporting spindle and tube by such movement. This frictional resistance force is by no means slight as it is not possible to provide a free and easy running bearing or support for the bobbin on the 65 stand and any drag force exerted on the wheel by It is therefore not feasible to place the yarn 70 under a sufficiently easy and uniform yielding tension by means of the drag, since the frictional resistance produced between the faces of the bobbin or the tube and of the spindle is considerable, however lavish the 75 lubrication may be.

This frictional resistance force to the rotation of the bobbin by the pull on the yarn tends to break the yarn, with the result that 80 yarn beyond a certain degree of fineness cannot be spun on machines of this kind, or at least the spinning of such yarn is accompanied with great difficulties and waste; fine 85 yarn, or loosely twisted yarn, or yarn made of inferior material cannot stand the sudden tensile strain of the pull thereon and 90 is broken.

The present invention is designed to overcome this disadvantage by providing the 95 following arrangement. The spindle is mounted in ball bearings on the lifter of fly frame and is freely and easily rotatable, and the bobbin engaged upon the spindle is positively coupled to the spindle by simple 100 means, such as a catch spring. Furthermore, the brake pulley or similar braking means is mounted on the lower end of the spindle, without any additional support or bearing, to rotate therewith. The spindle and its accessories therefore bear uniformly 105 on the ball bearings and the rotation thereof may be braked or retarded with an easy and predetermined force with the result that the tension on the yarn is easy, yielding and uniform to a degree which was not heretofore attainable.

The pulley or brake disk may be made of

metal and may be braked in the customary way by a drag member frictionally engaging therewith, such as a loaded cord 14, a helical spring or the like. Thus the friction 5 groove of the bobbin is dispensed with and the bore of the bobbin does not become worn and enlarged even after service of several years. A further advantage of the invention is that chattering and vibration of the 10 bobbins and of the spindle is eliminated. Moreover, the entire braking mechanism is protected from dust and dirt and so to speak invisible.

Two embodiments of the invention are 15 illustrated in the accompanying drawings as applied to a rotatably mounted lifter and flyer frame arranged with only a pair of bobbin carrying spindles and plates therefor, and the shaft is rotatable through an arc of 20 one hundred and eighty degrees for removing the bobbins from the spindles and engaging bobbins thereon, instead of embodying a plurality of bobbin carrying spindles and rotatable through an arc of ninety degrees 25 as is usual. While the lifter frame is described and illustrated as arranged with a pair of bobbins it will be obvious that the invention is applicable to spinning machines embodying a rotatably mounted lifter frame 30 arranged with a plurality of pairs of bobbin carrying spindles.

Fig. 1 is a part sectional elevation of one form of my invention.

Fig. 2 is a part sectional elevation of a 35 modification.

In the embodiment of the invention illustrated in Figure 1 the lifter or fly frame 7 is of box form mounted on a shaft 1 the axis of which is disposed in the plane of and intersects the axes of the spindles and flyer. The shaft with the frame is vertically reciprocatory to the extent of the length of the bobbin in the usual manner by lift rods 2. The active flyer 3 may be arranged in any desired position and is driven from a suitable source of power by a cord passing around pulley 4. Spindles 5 supporting a bobbin 6 on which the spun yarn is to be laid and on the other of which spindles the 50 bobbin containing the roving, as 6', to be drawn out and spun is engaged, are mounted in opposite walls of the lifter or fly frame to have free and easy rotation, an antifriction bearing such as a ball bearing 8 preferably being used for this purpose.

The bobbins 6 are positively coupled to the rotatable spindles by a resilient member 9 of spring wire arranged with a catch 11 normally urged laterally of the spindle and 60 adapted to engage a small recess 10 cut in the end of the bore of the bobbin and functioning to hold the bobbin against longitudinal movement on the spindle. While the catch 11 also serves to positively couple 65 the spools to the spindles whereby the spools

and spindles rotate in unison, a further means is provided to positively couple the spools and spindles together, and comprises a pin 9' fixed in and projecting from a flange 5' of the spindle for engagement in a 70 perforation in the spool flange juxtaposed to the spindle flange. This feature of the invention is utilized for applying a drag upon the spindle instead of on the bobbin by the pull on the yarn as it is spun and laid 75 upon one bobbin by the revolving of the flyer 3. A metal pulley 12 having a peripheral friction groove 13 has screw threaded connection with the lower end of the spindle 80 5 extending through the ball bearing into the lifter and fly frame, said pulley groove being frictionally engaged by a drag cord 14 yieldingly connected to the frame by a spring, as at 15, whereby the tension of the drag cord is adapted to be varied, the cord being passed through the eye of a member 16 fixed in the frame. Any other drag or brake means may be used in place of said cord. By this arrangement a very accurate 85 adjustment of the drag of the cord upon the wheel may be effected so that the resisting force to the tensile stress on the yarn will be of predetermined uniform degree, yielding and easy. Whether set for coarse or fine yarn the tension will thus remain the 90 same with the consequence that no further setting is necessary during the spinning operation. The entire drag or brake mechanism is mounted within the lifter frame and is protected from foreign substances, such as dust, 95 water or the lint thrown off from the fibre as it is spun. An important feature of this invention is that the braking mechanism is disposed close to the mounting of the spindle and any drag force exerted on the wheel by the drag is transmitted to the spindle bearing with the result that wear of the drag mechanism or the other parts is reduced to 100 a minimum. In view of the fact that the bobbin is not arranged as the drag pulley 105 the bobbin may be provided at both ends with flat, outwardly round flanges and thereby the cost of manufacture of the bobbins 110 reduced.

To remove or engage bobbins upon the 115 spindles the fly frame is rotated on the axis of the shaft 1 in the usual manner. After an empty bobbin has been engaged upon the spindle so as to come within the reach of the arms of a flyer a few turns of the yarn is wound upon the bobbins by the revolving of the flyer after which the yarn is broken. To guide the roving from the spool 6' to the flyer 3 guide rolls 17' are mounted upon rods 17 journaled by means of ball bearings 120 upon the lifter frame over which the roving is engaged.

In the embodiment of the invention illustrated in Figure 2 the shaft 1 instead of being positioned in the plane of and intersect- 125

ing the axes of the spindles, it is mounted forwardly or laterally of the flyer and the lifter frame is in the form of a pair of plates fixed to and extending oppositely in the same 5 plane from said shaft. The bobbin carrying spindles are mounted on said plates to extend from opposite sides. This construction of lifter frame is cheaper to manufacture but its operation is in all respects like 10 that of the Figure 1 construction. To protect the drag or brake mechanism from the accumulation of foreign substances thereon plates 18 are fixed upon the connection of the lifter plates with the shaft 1 to extend in 15 parallel relation to the lifter plates.

Experiments have shown that for example jute yarn No. 6^s Engl. could be spun without difficulty with the ordinary low degree of twist 1.1 with the flyers revolving at 20 about five thousand revolutions per minute. This result was heretofore thought to be impossible because there were no means of producing the soft and resilient drag afforded by the present invention.

25 What I claim is:—

1. In a spinning machine, a lifter frame, a spindle having a floating bearing in said frame, one end of said spindle projecting from one side of the frame for engagement 30 of a bobbin thereon and arranged with means for positively coupling and releasably holding a bobbin on the spindle, and a friction wheel constituting one member of a brake mechanism to retard the rotation of 35 the spindle fixed to the spindle at the opposite side of the lifter frame in proximity to the bearing of the spindle in the lifter frame.

2. In a spinning machine as claimed in 40 claim 1, adjustable means to frictionally and yieldingly engage the wheel to retard the rotation of the spindle.

3. A spinning machine as claimed in 45 claim 1, wherein the means to couple and releasably hold the bobbin on the spindle comprises a yieldable member of resilient wire mounted on the spindle arranged with a catch at one end of the spindle normally urged laterally thereof for engagement in a 50 recess in the wall of the bore of the bobbin engaged upon the spindle.

4. A spinning machine as claimed in claim 1, wherein the bearing of the spindle in the lifter frame comprises a ball bearing, means 55 to frictionally engage the wheel to retard the rotation of the spindle, and the wheel is arranged with a part overhanging the ball bearing whereby the stress of the force of the

friction means engaging the wheel will be taken up in the spindle bearing. 60

5. In a spinning machine as claimed in claim 1, means to frictionally engage the wheel to retard the rotation of the spindle, and the lifter frame is in the form of a housing enclosing the friction wheel and the 65 means engaging therewith to protect the same from the accumulation of foreign substances thereon.

6. In a spinning machine, a lifter frame comprising a pair of plates mounted on a 70 shaft whose axis is in a plane transverse to the axis of a flyer, a spindle rotatably mounted in each plate, one spindle to extend laterally from the side of one plate and the other spindle to extend laterally from the 75 opposite side of the other plate, friction wheels fixed to said spindles at the sides of the plates opposite to that from which the spindles project, and means carried by the plates to frictionally engage the wheels to retard the rotation of the spindles. 80

7. In a spinning machine as claimed in claim 6, means carried by the spindles to cooperate with a bobbin engaged on the spindles to positively couple the bobbins with the 85 spindles to rotate in unison therewith and releasably hold the bobbins upon the spindles.

8. A spinning machine as claimed in claim 6, wherein the lifter frame is adapted to be 90 moved about the axis of the shaft and have reciprocatory movement transverse to the axis of the shaft and in a direction longitudinally of the flyer.

9. In a spinning machine as claimed in 95 claim 6, means carried by the spindles to positively couple the bobbins engaged upon the spindles with the spindles, and the lifter frame is normally positioned with one spindle in axial alinement with the flyer and the 100 bobbin thereon adapted to take up the spun yarn, and the other spindle having a roving carrying bobbin engaged thereon, and means carried by the frame to guide the roving from the one bobbin to the flyer. 105

10. In a spinning machine as claimed in claim 1, means to frictionally and yieldingly engage the wheel to retard the rotation of the spindle, comprising a cord, a spring attached to a fixed part of the frame, and to 110 which the cord is attached, and a member fixed to the frame having an eye through which the cord is passed.

In testimony whereof I affix my signature.

HERMANN DEPPERMAN.
